STL file Cool 3D Lattice pen-cults3D.com,no publishing date,retrieved Apr. 10, 2023—U.S. Appl. No. 29/807,025—<https://cults3d.com/en/3d-model/gadget/3d-lattice-pen> (Year: 2023).*

Primary Examiner — Nicole C Shiflet*Assistant Examiner* — Danielle Nichole Bowly(74) *Attorney, Agent, or Firm* — PETERSON IP; Brett Peterson(57) **CLAIM**

I claim the ornamental design for a writing pen with lattice body, as shown and described.

DESCRIPTION

FIG. 1 is a front isometric view of the writing pen with lattice body.

FIG. 2 is a front view of the writing pen with lattice body.

FIG. 3 is a back view of the writing pen with lattice body.

FIG. 4 is a left side view of the writing pen with lattice body.

FIG. 5 is a right side view of the writing pen with lattice body.

FIG. 6 is a top view of the writing pen with lattice body; and, FIG. 7 is a bottom view of the writing pen with lattice body. The broken lines depict portions of the writing pen with lattice body that form no part of the claimed design.
